CLAIM

The ornamental design for a refuse and beverage holder for attachment to a lawn mower or the like as shown and described.

DESCRIPTION

FIG. 1 is a top and rear perspective view of a refuse and beverage holder for attachment to a lawn mower or the like showing my new design, the broken lines are for illustrative purposes only and form no part of the claimed design.

FIG. 2 is a front elevation view thereof;

FIG. 3 is a side elevational view thereof, the opposite side elevational view being a mirror image of that shown.

FIG. 4 is a rear elevational view thereof.

FIG. 5 is a top plan view thereof.

FIG. 6 is a bottom plan view thereof.
